UNITED STATES PATENT OFFICE.

HENRY MICHELSSEN, OF GARWIN, IOWA.

OILER.

1,212,086.

Specification of Letters Patent.

Patented Jan. 9, 1917.

Application filed May 31, 1916. Serial No. 100,821.

To all whom it may concern:

Be it known that I, HENRY MICHELSSEN, a citizen of the United States, residing at Garwin, in the county of Tama and State of Iowa, have invented new and useful Improvements in Oilers, of which the following is a specification.

This invention is an improved oiler for use in oiling machinery and the like, the object of the invention being to provide an improved device of this kind embodying an air pump for compressing air in the body of the oiler to force oil therefrom and also embodying a valve to control the delivery of oil and means to operate said controlling valve.

The invention consists in the features of construction, combination, and arrangement of devices, hereinafter fully described and claimed.

20 In the accompanying drawings:—Figure 1 is a sectional view of an oiler constructed and arranged in accordance with my invention. Fig. 2 is a detail elevation of the same at right angles to Fig. 1. Fig. 3 is a plan of the same with the delivery pipe or spout shown in section.

The tank or body 1 of my improved oiler is here shown as cylindrical, having a diametrically enlarged base 2 and also provided 30 with a truncated conical bottom 3 which has a threaded filler opening 4 and a plug 5 screwed in said opening. At the upper end of the body or tank is a nipple 6 to which a valve case 7 is screwed as at 8, a fiber washer 9 being provided to prevent leakage, and the delivery pipe or spout 10 is screwed to the upper end of the valve case as at 11. A turning valve plug 12 operates in a transverse opening through the valve case and 40 has a port 13, which when the said valve plug is turned in one direction, opens the bore of the valve case and when the valve plug is turned in the opposite direction, serves to cut off the same as will be understood. A lever 14 to operate the valve plug is attached as at 15 to the projecting end or head of the valve plug and said lever has a finger piece 15^a on its free end. The lever also has an arm 16 which projects from the 50 opposite side of the valve and to which a

stop 17 and a spring 18 are secured by a screw 19. The said stop is of inverted L-shape and serves to bear against the pipe or spout 10, when the valve plug is in open position to limit the opening movement of such 55 plug. The spring 18 is curved as shown and its free end bears and is slidable on the top of the tank and said spring exerts its tension, when the lever 14 is released by the operator to move said lever upwardly and 60 turn the valve plug to closed position and hold said valve plug normally in such position.

An oil intake pipe 20 is attached to the nipple as at 21, extends downwardly in the 65 center of the tank or body and has an intake arm arranged at an angle as at 22 and which extends to one side of the body at a point near the bottom thereof.

An air compressing pump 23 is arranged 70 on the side of the body, opposite the intake end 22 of the pipe 20 and its cylinder 24 is held in an eye 25 of a bracket arm 26 which is attached to the tank. The plunger of the air compressing pump is indicated at 27, the 75 plunger rod at 28, and the head of the rod at 29, said head forming a cap, which when the plunger is depressed, may be screwed to the upper end of the cylinder to secure the plunger against further operation. 80

The pump cylinder has a nipple 32 at its lower end which is secured to the casing 33 of a valve 34 which closes against the back pressure from the tank and permits compressed air to be forced by the air pump to 85 the tank where it presses downwardly on the body of oil in the tank and hence when the valve 13 is opened, causes oil to be forced pneumatically through the pipes 20 and 10, as desired. 90

The cylinder of the air pump, forms a convenient handle for the oiler and enables the user to operate either the pump or the delivery valve by the thumb of the hand with which he grasps the cylinder. 95

Having described the invention, what is claimed is:

In an oiler of the class described, a tank having a delivery valve and a delivery spout at its upper side, said valve including an 100

element mounted for turning movement, a lever attached to said movable element of the valve to turn the same and provided with an arm, an inverted L-shaped stop attached to 5 said arm and arranged to engage the delivery spout and limit the movement of said valve element in one direction, and a spring

also attached to said arm of the lever slidably bearing on the top of the tank and serving to normally turn the valve to closed 10 position.

In testimony whereof I affix my signature.

HENRY MICHELSSEN.
